US00D487219S

(12) **United States Design Patent** (10) Patent No.: **US D487,219 S**
 Chudy et al. (45) Date of Patent: ** Mar. 2, 2004

(54) **HAND-HELD TOOL**

(75) Inventors: **Frederick C. Chudy**, Greenfield, WI (US); **John A. Pierman**, Kenosha, WI (US)

(73) Assignee: **Snap-on Technologies, Corp.**, Lincolnshire, IL (US)

(**) Term: **14 Years**

(21) Appl. No.: **29/179,306**

(22) Filed: **Apr. 8, 2003**

(51) LOC (7) Cl. **08-05**

(52) U.S. Cl. **D8/68**

CLAIM

The ornamental design for a hand-held tool, as shown and described.

DESCRIPTION

FIG. 1 is a perspective view of the hand-held tool;

FIG. 2 is a right side view of the hand-held tool;

FIG. 3 is a left side view thereof of the hand-held tool;

FIG. 4 is a top plan view thereof;

FIG. 5 is a bottom plan view thereof;

FIG. 6 is a front elevational view thereof; and,

FIG. 7 is a rear elevational view thereof.

The broken lines are shown in the views for illustrative purposes only and form no part of the claimed invention.
